SHADE ROLLER

Original Filed Nov. 13, 1920

Stewart Hartshorn
INVENTOR.

BY Dyer & Taylor
ATTORNEYS.

UNITED STATES PATENT OFFICE.

STEWART HARTSHORN, OF SHORT HILLS, NEW JERSEY, ASSIGNOR TO STEWART HARTSHORN COMPANY, OF EAST NEWARK, NEW JERSEY, A CORPORATION OF NEW JERSEY.

SHADE ROLLER.

Original application filed November 13, 1920, Serial No. 423,936. Divided and this application filed December 12, 1923. Serial No. 680,067.

To all whom it may concern:

Be it known that I, STEWART HARTSHORN, a citizen of the United States, and a resident of Short Hills, county of Essex, and 5 State of New Jersey, have invented a certain new and useful Shade Roller, of which the following is a specification.

The invention relates to window shade rollers and more particularly to such devices as are composed of a solid cylindrical section or sections, and a tubular sheet metal section or sections whereby the length of the roller may be adjusted, but it is to be understood that the invention is not limited 10 to such use, but may be employed in other situations.

The invention is illustrated in connection with a shade roller of the spring action type, but it is desired to have it understood that the same may be carried out in 20 connection with rollers of other types, and with curtain poles or the like.

The objects of the invention are to provide cheap and efficient means for securing 25 a tubular extension to a solid roller, or a solid cylindrical extension to a tubular roller; to produce a combination wood and metal roller which will have all of the strength and rigidity of the wooden roller 30 and all of the advantages of the metal roller; to produce a roller in which the wood and metal elements may be readily assembled, and in which the said elements are locked in position by means of the shade 35 fastening means; to produce a roller in which the amount of wood will be reduced to a minimum and in which waste in boring and turning will be eliminated, and by means of which the liability of the wooden 40 portion to warp will be reduced whereby partly seasoned, and, therefore, cheaper wood may be employed.

These and further objects will more fully appear in the following specification and 45 accompanying drawings considered together or separately.

One embodiment of the invention is illustrated in the accompanying drawings in which like parts in all of the several figures are designated by corresponding characters of reference, and in which

Fig. 1 is an elevation of a shade roller embodying the invention, the shade being omitted.

Fig. 2 is a similar view taken at right angles of Fig. 1.

Fig. 3 is a transverse section, on an enlarged scale, taken on the line 3—3 of Fig. 1, the shade being shown in position.

Fig. 4 is an elevation showing a modification, and

Fig. 5 is an elevation of a roller illustrating a further modification.

In Figs. 1, 2 and 3 is illustrated a shade roller in which the major portion is of wood 65 and having an adjustable, tubular, metallic extension at each end thereof.

In Fig. 4 is shown a roller, the major portion of which is of tubular metal and which may have a wooden extension at 70 each end.

Fig. 5 shows a roller comprising a plurality of wooden sections alternating with metallic sections.

In Figs. 1, 2 and 3 the body of the roller 75 comprises a wooden element 1 of cylindrical form. One end of the element is bored to form a socket 2 in which the inner end of a rod 3 is supported, and said rod carries the usual winding spring 4.

Each end of the element is provided with a kerf 5, or a series of intersecting kerfs cut longitudinally of the element. The kerfs are of a width sufficient to permit the diameter of the element to be reduced at the 85 ends thereof by moving the tongues between the kerfs toward each other, because of the flexibility of the tongues.

Each end of the element is inserted in a tubular, metallic member 6 or 7, as the case 90 may be. The members are closed at the outer ends thereof and the closed end may carry the usual pintles, spears, etc.

The diameter of the element 1 is the same as the outside diameters of the members 6 and 7, but because of the kerfs the ends of the element may be inserted into the bores of the members and be maintained in position by the frictional engagement of the tongues with the walls of the members, and the ends of the element may be inserted to the desired depth in the members whereby the length of the roller, as a whole, may be adjusted.

Each member 6 or 7 is provided with a 105 perforation 8 in its wall near the closed end thereof, and when in proper position, the perforations are in alinement.

In applying a shade to the roller, one end of the shade is laid along the roller and approximately in alignment with the perforations 8 and covering the same, and is secured 5 in place to the roller by means of strips 9.

The strips are preferably curved laterally to conform to the surface of the roller, and each is provided with a pointed spur 10 projecting longitudinally therefrom but on a 10 different plane from the body of the strip. The opposite end of the strip is provided with an opening through which a nail or tack 11 may be inserted.

The spur is pushed through that part of 15 the cloth which covers a perforation 8, the strip is laid down on the edge of the shade cloth and the strip is pushed toward the closed end of a member 6 or 7, as the case may be. The movement will lock that end 20 of the strip to the member by the engagement of the spur with the interior wall of the member, and the cloth will be engaged between the strip and the roller.

The perforated end of the strip is now 25 tacked to the element by means of a fastening passing through the perforation and cloth. The cloth is now turned back over the strips and wound upon the roller.

The strips 9 not only serve to secure the 30 shade to the roller between the spurs and the tacks, but the said strips rigidly secure the members to the elements.

If desired, additional strips 12 may be 35 tacked along the end of the cloth whereby the cloth will be secured to the roller a practically the entire length of the roller, but the edge of the cloth will be perforated or cut at infrequent intervals.

That portion of the element 1 between the 40 members 6 and 7 is, with the exception of a short space near each member, of the same diameter as the outside diameters of the members and the edge of the cloth will be supported for practically the entire length 45 of the roller.

In the form of the invention illustrated in Fig. 4 the major portion 13 of the roller is tubular, and may be provided at each end with a wooden extension 14 whereby the 50 length of the roller may be adjusted.

Near its end the element 13 is provided with a perforation 15 into which the spur may be inserted. The opposite end of the strip 55 may be nailed directly to the extension, but preferably said end rests upon a sheet metal cup 16 into which the end of the extension is inserted, and the nail will pass through the strip, cloth and cap, and into the extension whereby the cloth and strip 60 will be secured to the cap and the latter to the wooden extension. The extension is preferably kerfed whereby it will frictionally engage the bore of the element 13.

Fig. 5 shows a roller comprising a plural- 65 ity of relatively short wooden sections 17

each being kerfed at its ends. The opposed ends of the section are joined by a metal tube 18 by inserting the ends of the sections in the tube, and the outer ends of the sections engage in the members 6 and 7 as 70 before. A shade may be secured to the roller and the parts thereof may be secured together as in the form of device shown in Figs. 1, 2, 3 and 4.

This application is a division of applicant's co-pending application for patent entitled "Shade fastening," filed November 13, 1920, Serial No. 423,936. 75

In accordance with the provisions of the Patent Statutes the principle of the invention has been described, together with the apparatus which is now considered to represent the best embodiment thereof, but it is desired to have it understood that the apparatus shown is merely illustrative, and that the invention may be carried out in other ways. 80

The invention having been described, what is claimed as new and desired to be secured by Letters Patent, is as follows: 90

1. A device of the character described, comprising a tubular member, a cylindrical element adapted to form a continuation of the member, the normal diameter of said element from end to end being greater than the bore of the member, there being a longitudinal kerf in the element, said kerf extending through the end of the element whereby its diameter may be reduced to permit of the element being inserted in the bore of the member. 95

2. A device of the character described, comprising a tubular member, a cylindrical element adapted to form a continuation of the member, the normal diameter of said element from end to end being greater than the bore of the member, there being a plurality of longitudinal kerfs in the element, said kerfs extending through the end of the element, whereby its diameter may be reduced to permit of the element being inserted in the bore of the member. 100

3. A device of the character described, 105

comprising a tubular member, a cylindrical element adapted to form a continuation of the member, the normal diameter of said element from end to end being greater than the bore of the member, there being a plurality of intersecting longitudinal kerfs in the element, said kerfs extending through the end of the element, whereby its diameter may be reduced to permit of the element being inserted in the bore of the member. 110

4. A device of the character described, 115 comprising a pair of tubular members, a cylindrical element the ends of which are adapted to engage one within each member to form a continuous body, the normal diameter of said element from end to end being greater than the bores of the mem- 120

bers, there being a longitudinal kerf extending inward from each end of the element whereby the diameters of the ends may be reduced to permit of said ends being inserted in the bores of the members, said kerfs extending part way of the length of the element whereby a portion thereof will be a solid cylinder.

5 5. A device of the character described comprising a pair of tubular members, a cylindrical element the ends of which are adapted to engage one within each member to form a continuous body, the normal diameter of said element from end to end being greater than the bores of the members, there being a plurality of longitudinal kerfs extending inward from each end of the element whereby the diameters of the ends may be reduced to permit of said ends 10 being inserted in the bores of the members, said kerfs extending part way of the length

15 of the element whereby a portion thereof will be a solid cylinder.

6. A device of the character described comprising a pair of tubular members, a 20 cylindrical element the ends of which are adapted to engage one within each member to form a continuous body, the normal diameter of said element from end to end being greater than the bores of the members, there being a plurality of intersecting longitudinal kerfs extending inward from each end of the element whereby the 25 diameters of the ends may be reduced to permit of said ends being inserted in the bores of the members, said kerfs extending part way of the length of the element whereby a portion thereof will be a solid cylinder.

30 35 This specification signed and witnessed this 30th day of November, 1923.

STEWART HARTSHORN.
